DESIGN FOR A FRUIT JUICE EXTRACTOR

Joseph M. Majewski, Jr., Kansas City, Mo., assignor to Foster L. Talge, Kansas City, Mo., doing business as Rival Manufacturing Company

Application March 4, 1937, Serial No. 67,983

Term of patent 14 years

To all whom it may concern:

Be it known that I, Joseph M. Majewski, Jr., a citizen of the United States, residing at Kansas City, in the county of Jackson and State of Missouri, have invented a new, original, and ornamental Design for a Fruit Juice Extractor, of which the following is a specification, reference being had to the accompanying drawing forming part thereof, in which

The salient feature of the design is shown in full lines.

I claim:

The ornamental design for a fruit juice extractor substantially as shown and described.
